(57) **CLAIM**

The ornamental design for a bar shed, as shown and described.

DESCRIPTION

FIG. 1 is a top, front, and left perspective view of the bar shed of the present invention, with the windows and doors shown in a closed position;

FIG. 2 is a top rear right perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a top, front, and left perspective view of the bar shed with the doors and windows shown in an open and operational position.

The portions of the bar shed illustrated in broken lines form no part of the claimed design.

1 Claim, 8 Drawing Sheets
